UNITED STATES PATENT OFFICE.

FREDERIC W. HILLARD, OF TOTTENVILLE, NEW YORK, ASSIGNOR TO TYPEWRITERS
HILLARDIZED INCORPORATED, A CORPORATION OF DELAWARE.

TYPEWRITER.

Original application filed February 27, 1919, Serial No. 279,545. Divided and this application filed September 3, 1920. Serial No. 408,013.

To all whom it may concern:

Be it known that I, FREDERIC W. HILLARD, a citizen of the United States, residing at Tottenville, Staten Island, county of Richmond, and State of New York, have invented certain new and useful Improvements in Typewriters, of which the following is a full, clear, and exact description.

This application is a division of a pending application, Serial No. 279,545, filed February 27, 1919, upon which issued Patent 1,356,282, October 19, 1920, which in turn was filed as a division of a prior application, Serial No. 103,758, filed June 15, 1916, upon which issued Patent Number 1,296,957 on March 11, 1919.

The invention upon which the present application is based is an improvement in anti-friction or ball bearing supports for the carriage of a typewriter. The improvement is herein illustrated as applied to the well known Underwood typewriter for which instrument it was particularly designed but this is illustrative only as the invention has a wide application and is not limited to any special form of machine, but applicable generally where the other features of construction and operation permit.

The chief object of the invention is to secure an easy running and rapid feeding carriage in a visible typewriting machine and at the same time provide a carriage which may be readily swung upward so that the parts of the mechanism thereunder may be readily inspected, repaired and cleaned. This swinging movement of the carriage also is an advantage in that the writing may be inspected practically to the last line on the sheet and the operator by so swinging the carriage can readily tell just how much space is left at the bottom of the sheet or card.

In carrying out this part of my invention I provide a truck at the rear of the machine which truck is always locked against shifting movement. The truck is provided with an improved ball bearing antifriction support and raceways therefor, so that the truck may move sidewise with the minimum of friction. To this truck is pivoted a carriage structure.

My invention also contemplates, an im-

proved friction brake for tabular use which brake is associated with the before mentioned truck in such a way that the speed of the feeding movements of the truck may be reduced to any desired extent by means of the pressure applied to the bearing balls by the tabulating key.

The invention involves also certain features of construction in the details of the mechanism but these will be more fully pointed out in the description which follows.

In the accompanying drawings which illustrate the improvements in typewriting machines for which I now seek the protection of Letters Patent,

Fig. 1 is a plan view of the complete machine.

Fig. 2 is a side elevation of the upper or carriage portion of the machine.

Fig. 3 is a front view of the truck showing the application of the improvement.

Fig. 4 is an end detail view of one of the parts of the truck known as a cage.

Fig. 5 is a central sectional view of the truck and its means of support.

Fig. 6 is a plan view of the ball bearing cage and raceways.

Fig. 7 is a rear view of the truck and its associated parts.

Figs. 8 and 9 are detail views of the locking device for the carriage showing the relation thereto of the ball bearings.

Figs. 10 and 11 are cross sectional views of the parts shown in Fig. 7 given for illustrating the relation of the raceways to such parts.

Figs. 12 and 13 are sectional details of modified bearing constructions in which rollers are used in place of balls, spacing balls being also shown therein.

Fig. 14 shows detached the elements of the rear margin stop for the carriage.

Referring more particularly to Figs. 1 and 2 the preferred embodiment of my invention comprises a truck 1. Extending forwardly and upwardly from this truck are brackets 2 which pivotally support a shaft 3. This shaft forms a pivotal support for both the inner and outer carriage. The outer or non-shiftable carriage is shown at 4, and on this carriage are rearwardly ex-

tending lugs 5 which pivotally engage shaft 3, Fig. 1. The inner or shifting carriage is shown at 6, and this carriage is provided with suitable sockets or brackets which support 5 studs which pivotally engage in the forward ends of the shift arms 7. The bearings in the forward ends of these shift arms are closed over with caps 8, instead of being open as in the ordinary Underwood machine since 10 it is necessary that the carriage be retained in position when swung upwardly. The opposite or rear ends of the shift arms 7 are fixed to the ends of shaft 3.

The inner shifting carriage is adapted to 15 be vertically raised and lowered by any of the well known shift constructions, but as these are well known in the commercial Underwood machine, further description and illustration is believed to be unnecessary.

20 The front end of the outer carriage 4 is provided with the usual supporting wheel which travels on the front guide rail 9. It is also provided with a locking finger which underlies a slot in the upper front rail 10. 25 This is the usual construction. The hinge joint at 3 between the carriage and the truck permits the carriage to adjust itself to its position on guide rail 9, and prevents friction by undue pressure against either of the 30 front rails.

In the usual Underwood construction 35 there is no truck, the carriage being mounted upon a fixed guide rail. The advantage of the truck over the fixed guide rail is that antifriction devices may be more readily applied thereto. Furthermore, the hinging of the carriage to the truck 1, permits the truck to assume its correct vertical position in raceways 11, 12 and at the same time allows 40 the carriage to rest properly on the front guide rail.

The truck 1 is mounted upon the machine frame in the following manner. Two upwardly projecting arms 13 extend from the 45 machine frame. Upper and lower raceway rails 11 and 12 are secured to these arms and are preferably adjustable to and from each other. As shown in Figs. 7, 8 and 9, the upper raceway 11 is adjustable towards the lower raceway 12 by means of adjusting 50 screw 14. The truck 1 has upper and lower raceways which are oppositely disposed to the upper and lower raceways 11 and 12.

It will be obvious, in the construction 55 above described, that the hinged or linked connection at 3 between the carriages 4, 6 and the truck 1 is of very great importance. The structure is practically a three bearing one, one of the bearings being the upper 60 raceway 11 for the truck 1, the second one being the lower raceway 12 for the truck and the third one the front support 9 for the carriage 4. There is also a fourth bearing point for the inner carriage 6, that is 65 to say the support wheel 42 resting on the

shift-rail 43. The entire structure therefore may be said to be a four point bearing so far as the running bearings are concerned, taking into account the truck 1, the outer carriage 4 and the inner carriage 6.

It is obvious that in order to properly maintain and control the carriages 4, 6 in their proper printing positions, the truck 1, which constitutes the main support between the carriages and the frame of the machine, 75 must be closely fitted upon its ball-bearings in the upper and lower raceways. Therefore, there must be a snug fit between the ball-bearings in all of the raceways and each bearing ball must rest at four points, viz., 80 on each side of each raceway in the truck 1 and on each side of the raceway in each of the guide-rails 11 and 12. Moreover, in order to secure the best results the supporting strain on each of the balls 15, 15 in 85 each of the raceways should be uniform on all the four said bearing points. Since the guide-rails 11 and 12 are stationarily mounted upon the machine frame, with their raceways correctly lined up with each other, 90 it is obvious that the truck 1 should be free to assume its correct vertical position so that its raceways will line up correctly with the corresponding raceways in the guide-rails 11 and 12. Then when the upper guide-rail is properly adjusted down by the adjusting 95 screw 14 the entire set of bearing balls 15, 15 will be snugly and still freely held in the raceways between the truck 1 and its upper and lower guide-rails 11 and 12. 100 Under these circumstances there will be no looseness of the truck within the guide-rails, and yet the anti-friction character will be fully maintained.

The importance of the linked or hinged 105 connection between the carriage and the truck thus becomes apparent. If the carriage 4 were not linked to the truck but were rigidly connected thereto, it would be practically impossible, as a manufacturing 110 proposition, to be assured that the carriage 4 would rest on its front guide-rail 9 without causing more or less detrimental side strain of the truck 1 bodily rearwardly or forwardly out of its correct vertical position in guide-rails 11 and 12. For instance, if the front guide-rail 9 were mounted in the machine even a very little too low or the front guide-wheel were in the least too small in diameter or mounted at all too high 115 on the carriage, the weight of the carriage, in the position where its front guide-wheel would rest on the front guide-rail 9, would cause the truck 1 to lean bodily forward more or less in its guide-rails 11 and 12, thus causing a detrimental strain and friction upon the bearing balls 15, 15 which would increase according to the extent the carriage should lean forward from its true 120 vertical position. The reverse condition 125

would arise, the truck being inclined bodily rearward out of its true vertical position and thus causing an objectionable strain on the balls in the raceways resulting in excessive friction, if the position and mounting of the front guide-rail 9 or front guide-wheel were such that the carriage were lifted above the point for bringing the truck into its true vertical position. This on the assumption that the truck and carriage were made rigid with each other.

In the present construction, as above described, the outer carriage 4 and the inner carriage 6 are each independently hinged or linked to the truck 1. Hence both of them are flexible relatively to the truck and neither of them can impart thereto the objectionable strain which would be present, as above pointed out, were not these hinged or flexible linked connections provided between the inner and outer carriages and the truck.

Another advantage of the ball-bearing truck and linked carriage construction here shown, is that this arrangement prevents the objectionable friction in the bearing heretofore present (in the construction wherein no truck is employed), caused by the twisting pull of the main spring. As above stated the present truck arrangement and linked carriage permits the carriage and truck to properly adjust themselves to their relatively correct positions without undue pressure and friction in the ball-bearing raceways. The main spring is directly connected to the outer carriage frame 4 and the escapement rack is also pivoted upon the same frame. The pull of the main spring through bracket 44 is slightly to the rear of the escapement rack 45, so that the pull of the main spring and the restraining influence of the escapement rack 45 and pinion 46 are out of line with each other. Therefore the main spring (not shown, but which is of the usual construction) through its connection with the carriage by flexible tape constantly tends to draw the rear part of the carriage forward or to the left in the line of print, the carriage being restrained by the escapement pinion 46 and carriage rack 48 and released by the escapement for its step by step movement as the keys are operated. Under this construction it is obvious that there is never any slack in the movement of the carriage, while on the other hand the carriage is held rigidly in line because the ball-bearing truck, being flexibly connected with the carriage, is free of twisting strains and therefore the truck can be very closely mounted on the bearing balls in the raceways.

In the above described raceways I utilize ball or roller bearings to minimize friction. I preferably use the arrangement shown in Figs. 3, 5 and 6. I use three balls to each bearing, there being four bearings in the machine, two in each raceway. The outer

balls 15 of each bearing are of full standard size to fill the raceway, whereas the intermediate balls 16 are of slightly smaller diameter. The function of the small ball 16 between the large balls is to reduce friction 70 by causing the bearing surfaces of the outer balls to travel in the same direction instead of travelling against each other as would be the case if there were only two balls in each bearing.

In ball bearing structures for many typewriter carriages heretofore in use, one ball has been provided for each bearing, with the result that there is a single bearing point only between the raceways and balls at each 80 bearing. Hence any imperfections in the raceways in the line of travel of the bearing balls would disadvantageously affect the bearing, making a bearing loose at one point and tight at another. By putting the two 85 balls in each bearing, particularly if they be spaced a little way apart by an intermediate spaced ball, much better results are obtained since if one of the bearing balls in the bearings drops into a little pit or hollow in the 90 raceways, the other bearing ball in the same bearing will presumably be resting on a perfect portion of the raceway bearings. Furthermore, by having two bearing balls in each bearing, or eight bearing balls in all the 95 four bearings instead of four altogether as in those heretofore in use, much more durable bearings are provided, the weight of the truck and carriage being distributed over double the number of bearing balls, resulting 100 in greatly lengthening life in the bearings over those heretofore in use.

It will be understood that I may use rollers in place of balls if desired. If desired the construction shown in Figs. 12 and 13 105 may be utilized where rollers 17 carry the load and are spaced apart by a spacing ball 18, of less diameter than the rollers 17. In the claims the item "roller" is to be considered a broad term referring to either a ball 110 or roller construction. The balls or rollers and their retaining cap 19, move at one-half the speed of the movement of the truck and carriage, as will now be described.

Upon the front of the truck 1 and adapted 115 to travel in unison therewith, is a downwardly facing rack 20 which engages a pinion 21 carried by the ball retainer. The ball retainer has one portion 22 in the upper raceway and another portion 23 in the lower 120 raceway. Upon the lower raceway 12 I mount a second rack 24 which also meshes with pinion 21. The result of this construction is to move the ball retainer at one-half the speed of the truck thereby always retaining 125 the balls in their proper position in the raceways and preventing what is known as a creeping movement. This creeping of the balls would otherwise take place where short lines of work are written for any consider- 130

4
able period of time. The balls then gradually creep out of position so that when a longer line is written they would come to the end of their line of travel before the truck 5 had reached such a point. The ball retainer 19 causes practically no friction since it is geared to travel at proper speed with respect to the rack.

As previously explained the truck 1 has 10 upwardly projecting arms or brackets 2 which partially support shaft 3. The lifting or shifting arms 7 are pinned to the ends of this shaft and the usual spring 25 is coiled about this shaft to assist in lifting 15 the inner carriage 6. I also employ another spring to assist lifting of the shift-rail and inner carriage to upper case position but as this spring is similar to the corresponding spring used for the same purpose 20 in the Underwood machine, it is not shown.

Upon the rear side of the truck there is 25 mounted a plate 26 which serves both as a margin stop for the truck and carriage. This plate forms one of the elements of the tabulator which will now be explained. The tabulator key and connecting links are the same as in the Underwood machine and need not be described in detail. Referring to Figs. 10, 11 and 14, 27 represents a pull 30 bar operated by the tabulator key which, for reason given, is not shown, which rocks rocker arm 28, which, in turn, swings the tabulator bar 29 rearward, and tabulator bar 30 and tabulating stop 31 forward. These 35 parts operate substantially as do the corresponding parts in the Underwood machine. The friction bar 30 presses against a brake leather 32 which is carried upon the plate 26, which plate is supported upon the plate 26, which plate is supported upon 40 and moves in unison with the truck. The pressure against the brake leather has the usual retarding effect upon the movement of the truck and in addition, the pressure against the leather tends to push the entire 45 truck, particularly the upper half thereof, forward and to thereby crowd the bearing balls 15 between the raceways 11 and 12 and the corresponding raceways on the truck 1. This crowding of the bearing balls 50 against their raceways constitutes an additional extremely sensitive and reliable brake, in fact a more reliable brake than the leather brake, which is liable to wear. It is understood that I claim this feature broadly and 55 do not limit its use in combination with the sliding brake. It may be so used or the sliding brake can be omitted, or it can be used in combination with other forms of the brakes. The detailed description of the operation 60 of the tabulator need not be set forth as the action is similar to that of the well known Underwood tabulator.

By referring to Figs. 1 and 2 it will be seen that the upper front rail 10 is notched 65 as shown at 33. This notch permits the nose

of the locking finger to escape from its normal position below the front rail 10, when it is desired to elevate the carriage. I preferably place the notch near the right hand end of the rail, but it may also be placed 70 in other positions. The usual Underwood margin stops may be employed. Briefly

stated these stops comprise abutment members 34 which can be set in any desired position. As the carriage advances a nose portion 75

35 of margin release lever 36 contacts with the abutment and prevents a further movement of the carriage to the right. To further move the carriage to the right it

is necessary to depress the margin release 80 lever and free the nose from the abutment. The extreme right movement of the carriage

is also limited by a rear margin stop which is shown in Fig. 7 and in detail in Fig. 14. This margin stop comprises the plate 26 85

which is rigidly connected with the truck 1. This plate has an upwardly projecting portion 37. Suitably secured by screws to this

portion of plate 26 is an L-shaped piece 38. The screw holes in this piece are slightly 90

elongated so that the piece 38 can be set at any desired longitudinal position with respect to plate 26. The L-shaped piece 38

carries dowels which cooperate with holes in shim pieces 39. By using shim pieces of 95

different thickness the position of the L-shaped piece 38 can be set very accurately. When the carriage moves to the right, the end 40 of the L-shaped piece finally abuts 100 against the side frame bracket 13, which supports the upper raceways 11 and this limits the extreme movement of the carriage and truck. Brake leather 32 clears bracket 13, see Fig. 2.

The purpose of the herein described elements of the back margin stop is to bring the face 40 of the L-shaped piece 38 at exactly the proper position for bringing the carriage to the starting point. This is a

very particular adjustment in typewriting 105 machines, because if the engaging face of the margin stop be slightly too far to the right or left, the carriage is apt to be brought back either not far enough and begin the margin a little space too far to the left or to 110

be brought back too far and begin the margin of the line within the marginal space making a bad looking page of writing. The shims 39 prevent the blow of the re-

turning movement of the carriage from over- 115 coming the frictional hold of the screws and crowding the L-shaped plate 38 along relatively to the retaining plate 26. These shims also aid in manufacturing since it is

practically impossible to make all of 120 the parts, such as truck, margin stop and escapement exactly interchangeable. The shims and mechanism for inserting and

holding them overcome this defect very 125 efficiently and quite inexpensively.

Having now described my invention what I claim is:

1. In a typewriting machine, the combination of a truck, ball-bearing raceways therefor, a carriage in front of the truck and connected thereto by a link connection at its rear edge and guided at its front edge for straight line letter-spacing movements, a main spring directly connected to the carriage and a rack mounted on the carriage and engaging an escapement pinion to control the carriage against the pull of the main spring.
2. In a typewriting machine, the combination of a truck, ball-bearing raceways therefor, a carriage in front of the truck and connected thereto by a single hinge connection at either end of the carriage and truck, said carriage being mounted at its front edge on a supporting wheel resting upon a front guide rail, a main spring for advancing the carriage in the line of print and an escapement to control the carriage against the pull of the main spring.
3. In a typewriting machine, the combination of a truck, ball-bearing raceways therefor, a carriage structure in front of the truck comprising an outer, non-shiftable carriage connected to the truck by a link connection at its rear edge and mounted at its front edge on a supporting wheel resting upon a front guide-rail, and an inner carriage the latter being also independently linked at its rear edge to the truck and being mounted upon a supporting wheel upon a shift-rail for a shifting movement independent of the outer carriage, a main spring for advancing the carriage in the line of print and an escapement to control the carriage against the pull of the main spring.
4. In a typewriting machine, the combination of a truck, roller-bearing raceways therefor, a carriage having a hinged connection with the truck, and means for restraining the carriage during letter-spacing movements to a straight line movement.
5. In a typewriting machine, the combination of a truck, roller bearing race-ways therefor, a nonshiftable carriage having a hinged connection with the truck, means for restraining the carriage during letter-spacing movements to a straight line movement, and a shiftable carriage mounted for shifting movements with respect to the non-shiftable carriage.
6. In a typewriting machine, in combination with ball bearing raceways, one being fixed and the other movable, a roller bearing in the said raceway, said bearing comprising a plurality of rollers, two of said rollers being of the same diameter and spaced apart by a single ball of less diameter, whereby upon relative movement of the raceways the outer rolling members rotate in the same direction and friction is thereby minimized.
7. In a typewriting machine, in combination, with roller bearing raceways, one fixed and the other relatively movable thereto, a pair of roller bearings in the said raceway, a travelling cage adapted to prevent creeping of the rolling members and to space the bearings apart in the raceway, each of said pair of roller bearings comprising three rolling members in contact with one another, the outer rollers being of such diameter to properly contact with the raceways and carry the load, and the intermediate rolling member being of less diameter, the said intermediate rolling member acting as a revoluble spacer for the other rolling members and preventing a rubbing contact between the outer roller members contacting with the raceways upon a relative movement of the raceways.
8. In a typewriting machine, in combination, roller bearing raceways, a roller bearing in said raceways, said bearing comprising a plurality of roller members, two being of greater diameter than the remaining intermediate roller member, said intermediate roller member, and the outer roller members of greater diameter moving with a rolling action in the same peripheral direction against one another upon the relative movement of the raceways.
9. In a typewriting machine, in combination, a plurality of roller bearing raceways, roller bearings therein, a tabulating device, and means in operative relation with the said tabulating device and one of the raceways for crowding the roller members in the raceway and thereby constituting a friction brake in the raceways.
10. In a typewriting machine, in combination, a truck, a plurality of roller bearing raceways, one of said raceways being operatively connected with the truck, roller bearings in the said raceways, a tabulating device, and means associated therewith for crowding the rolling members against their cooperating movable and stationary raceways, whereby the speed of movement of the truck is reduced during a tabulating operation.
11. In a typewriting machine, in combination, a plurality of roller bearing raceways, relatively movable with respect to each other, a brake element operatively associated with one of the raceways, a friction plate in operative relation thereto, and means for engaging the friction plate with brake element, whereby the speed of the relative movement of the raceways is diminished, said engagement of the plate and brake element being also adapted to crowd the roller members in the raceways, whereby the speed of movement of the raceways is further diminished.
12. In a typewriting machine, in combination, a margin stop for the movable carriage comprising a fixed abutment, a mem-

ber operatively connected with the carriage and a second member adjustably secured to the first member and adapted to contact with the fixed abutment and limit the extreme movement of the carriage.

13. In a typewriting machine, in combination, a ball bearing truck to support a carriage structure, fixed raceways to support the said truck, a margin stop having one member fixed to the truck and a second member adjustably secured to the first member and adapted to contact with a fixed abutment and limit the extreme movement of the truck.

14. In a typewriting machine, in combination, a carriage truck, a margin stop therefor, said margin stop comprising a fixed member attached to the truck, an adjustable member secured to the first mentioned member and a spacing member intermediate the first and second mentioned members to maintain the adjustment after it has once been set, said second mentioned member being adapted to contact with a fixed abutment upon the machine to limit the extreme movement for the carriage truck.

15. In a typewriting machine, in combination, a carriage truck, a combined margin stop and tabulator brake support, said device including a member fixed to the truck, a tabulator brake secured thereto, a longitudinally adjustable member connected thereto, and adapted to contact with a fixed abutment upon the machine and thereby limit the extreme movement of the truck, and a replaceable spacing member intermediate the longitudinally adjustable member and the member fixed to the truck to preserve the relative position of the adjustable and fixed members upon the impact against the fixed abutment.

16. In a front strike typewriter, the combination with a carriage-propelling power and an escapement, of a truck, a carriage having a hinged connection with the truck, means for restraining the carriage and truck to a straight line movement during the let-

ter-spacing movements, and brake means co-operating with the truck to control the speed of the carriage when released from the escapement.

17. In a typewriting machine, the combination with the carriage-propelling power and an escapement, of a truck, roller-bearing race-ways therefor having roller members therein, a carriage having a hinged connection with the truck, means for restraining the carriage to a straight line movement during letter-spacing movements, and brake means co-operating with the truck to crowd the roller members in the race-ways, and thereby constitute a friction brake for the carriage when released from the escapement.

18. In a front strike typewriter, the combination with the carriage-propelling power and an escapement, of a truck, a non-shiftable carriage having a hinged connection with the truck, means for restraining said carriage and truck to a straight line movement during the letter-spacing movements, a carriage mounted for shifting movements with respect to the non-shiftable carriage, and brake means co-operating with the truck to control the speed of the non-shiftable carriage when released from the escapement.

19. In a typewriting machine, the combination with the carriage-propelling power and an escapement, of a truck, roller bearing race-ways therefor having roller members therein, a non-shiftable carriage having a hinged connection with the truck, means for restraining said carriage and truck to a straight line movement during the letter-spacing movements, a carriage mounted for shifting movements with respect to the non-shiftable carriage, and brake means co-operating with the truck to crowd the roller members in the race-ways and thereby constitute a friction brake for the non-shiftable carriage when released from the escapement.

In testimony whereof I hereto affix my signature.

FREDERIC W. HILLARD.
